UNITED STATES PATENT OFFICE.

ANDREW S. SIMKO, OF PASSAIC, NEW JERSEY.

REMOVABLE HALF SOLE FOR SHOES.

Application filed April 22, 1926. Serial No. 103,940.

This invention relates to footwear and particularly to an improved easily applied and easily removable half-sole for shoes, the object being to provide a construction which will look and wear substantially the same as an ordinary half-sole as now made and applied while at the same time presenting a structure which may be readily applied and removed by any one.

Another object in view is to provide a removable half-sole for shoes wherein means are provided for clamping the same in position without removing the old sole or after removing the same.

A still further object of the invention is to provide a removable half-sole for shoes wherein a half-sole plate of leather or other material is provided with clamping means adapted to be snugly fitted over the edge of the permanent sole of the shoe.

In the accompanying drawing—

Figure 1 is a partly inverted perspective view of a shoe supplied with a removable half-sole, disclosing an embodiment of the invention.

Figure 2 is a perspective view of a half-sole, disclosing an embodiment of the invention.

Figure 3 is a bottom plan view of the structure shown in Figure 1.

Figure 4 is a sectional view through Figure 3 on line 4—4.

Figure 5 is a sectional view through Figure 3 on line 5—5.

Figure 6 is a fragmentary side view of the shoe shown in Figure 1 with certain parts broken away for illustrating how the clamping wire is positioned when in use.

Referring to the accompanying drawing by numerals, 1 indicates a shoe of any desired kind provided with the usual sole 2 which may be held in place by stitches. When the sole 2 becomes worn, as for instance, under the ball of the foot, it is quite customary to cut away the front part and then apply a new half-sole thereto. The new half-sole may be stitched in place or may be held in place by tacks or nails. This way of applying a half-sole requires the service of an experienced shoemaker and involves some expense.

In the present invention, a removable half-sole 3 has been provided which may be applied by an experienced person or an inexperienced person and is designed to be ap-

plied over the old worn sole, though if desired, the same could be cut away leaving the inner sole and welt. The removable half-sole 3 is preferably provided with a half-sole plate 4 of leather to which is secured 60 a binding strip 5 also of leather. The plate 4 is preferably thick heavy leather commonly used as half-soles while the strip 5 is preferably a thin flexible strip of leather as commonly used on the uppers. The strip 5 is stitched to the plate 4 by a line of stitching 6 and is also provided with a line of stitching 7 whereby a looped portion is presented for receiving the cable or wire 8. The wire 8 extends the full length of the strip 5, that is, along one side of the plate 4, across the front end and on the opposite side. Preferably, the ends 9 and 10 project an appreciable distance beyond the strip 5 so that they may be readily inserted or forced 75 through the apertures 11 and 12 in sole 2.

In applying the half-sole shown in Figure 2, the same is put substantially flatwise over the front part of the sole of the shoe until it assumes substantially the position shown 80 in Figure 1. The edge of strip 5 carrying the wire 8 is then forced by a pair of pliers or other instrument over into substantially the position shown in Figure 4 so that the strip 5 will be looped over the edge of the old half-sole or the welt. When the looped portion carrying wire 8 has been thus positioned, the ends 9 and 10 are pulled under as much tension as possible and then bent 85 back upon themselves over the outside of 90 the sole 2 as indicated in Figures 1 and 5. Preferably the holes 11 and 12 are positioned so as to be almost, if not entirely, covered by the rear edge portion 13 of the half-sole plate 4. After the ends 9 and 10 95 have been pulled as described, a few tacks or nails 14 are forced into position and the work of applying the half-sole has been completed. As the strip 5 is of leather of a rather high grade, the same will give the edges of the welt or old sole a nice appearance whereby the finished half-soled shoe will have substantially the same appearance as it originally had when new.

In case the removable half-sole should become worn to an undesirable extent, the same may be readily removed by raising the rear edge portion 13, unbending the ends 8 and 9 and pulling these ends through the holes 11 and 12. This releases the half- 105 110

sole which may then be bodily moved away from the shoe and a new half-sole provided.

What I claim is:

The combination with a shoe having openings in the sole near the instep, of a removable half sole adapted to fit over the front part of the sole of said shoe and extend to a position substantially over said openings, said removable half sole including a flexible member extending from the edge over the edges of the sole of the shoe, a wire tension member mounted in one edge for the full

length of said flexible member and extending through said openings for clamping the edge of the flexible member against the upper part of said sole, the ends of said wire being bent to rest against said sole and beneath the end of said half-sole, and fastening means extending through said half sole near the instep and acting to clamp said half sole against said bent ends for locking the same in position. 15 20
